UNITED STATES PATENT OFFICE.

HARRY E. CAMPBELL, OF NEW YORK, N. Y.

WINDOW FRAME AND SASH.

1,426,458.

Specification of Letters Patent. Patented Aug. 22, 1922.

Application filed November 30, 1921. Serial No. 518,756.

To all whom it may concern:

Be it known that I, HARRY E. CAMPBELL, a citizen of the United States, residing at New York, in the county of New York and 5 State of New York, have invented a certain new and useful Improvement in Window Frames and Sashes, of which the following is a specification.

The invention relates to window-frames 10 and sashes of the type shown, for example, in U. S. Letters Patent No. 1,273,453, granted to me July 23, 1918, and consists in the construction of the window-frame whereby the sashes may be easily removed therefrom 15 for packing for transportation, or for repair or replacement. The frame and sashes, as here shown, may be of wood or wood covered with sheet metal. The lateral extension plates on the sashes which enter the 20 hollow jambs are here shown of metal and cooperate with fixed metal walls or partitions within said jambs.

In the accompanying drawing—

Fig. 1 is a transverse horizontal section 25 of the sashes and frame. Fig. 2 is a vertical section on the line 2, 2 of Fig. 1. Fig. 3 is an elevation of a portion of the middle section 11, showing the joint between the parts of said section.

Similar numbers of reference indicate like 30 parts.

3 and 4 are hollow jambs of wood. As these jambs are alike, a description of one applies to both. The front wall 5, the rear 35 wall 6 and the outer side wall 7 are of planking framed together. The inner wall is composed of four vertical sections, namely, an inner section 8 secured to rear wall 6 by screw 9, an outer section 10 which is rabbed to receive the end of the front wall 5 and which protrudes outwardly beyond said front wall, and two middle sections 11 and 40 12. The middle section 11 is carried by a fixed metal wall 13 within the jamb. Said 45 wall 13 is secured between the front wall 5 and outer section 10 by the screw 14 which unites said wall and section and passes through said fixed wall 13. The middle section 11 is secured to said fixed wall 13 by 50 countersunk screws 15 and is made in two parts 16, 17 disposed one above the other, as shown in Fig. 3, the joint 18 between them being preferably diagonal. The middle section 12 is secured by screws 19 to the middle 55 section 11 and has its inner surface flush with the adjacent inner surfaces of sections

8 and 10. Vertical gaps are left between the edges of section 12 and the adjacent edges of sections 8 and 10, through which pass metal extension plates 20 and 21 which 60 are secured on the vertical side rails of the sliding sashes 22, 23. These extension plates at their free edges move over the vertical surfaces of the fixed walls 13 when the sashes are raised or lowered. In Fig. 1, 23 65 is the upper and 22 the lower sliding sash, each carrying, as usual, a glass pane 24.

To remove the lower sash 22, I simply remove the screws 9, and so release the jamb wall sections 8. The sash is then moved inwardly into the room. To cause its extension plates 20 to pass the rear jamb walls 6, it is also moved laterally in its own plane into first one hollow jamb and then into the other, so that the extension plate first on one 75 side of the sash and then on the other successively clear said walls.

To remove the upper sash 23 (the lower sash having been removed) the middle section 12 and the upper portion 16 of section 80 11 are taken out, when said sash can be moved inwardly into the room and caused to clear the rear jamb walls 6 in the same way as already set forth in connection with lower sash 22.

I claim:

1. In combination, two sliding sashes having lateral extension plates on their side rails, a frame having hollow jambs, each jamb comprising a fixed wall, wherewith 90 said extension plates cooperate, and an inner wall formed in four removable sections, to wit, an inner section, an outer section and two middle sections, one of said middle sections being secured to said fixed wall and 95 the other of said middle sections being secured to said first-named middle section; there being gaps for the reception of said extension plates between the edges of said last-named middle section and the edges of 100 the inner and outer sections adjacent thereto.

2. The combination of claim 1, further including said one middle section made in separately removable parts disposed one above the other.

In testimony whereof I have affixed my signature in presence of two witnesses.

HARRY E. CAMPBELL.

Witnesses:

GERTRUDE T. PORTER,
MAY T. McGARRY.
